(57) **CLAIM**

The ornamental design for a garment, as shown and described.

DESCRIPTION

FIG. 1 is a top plan view of a garment, showing my new design. The garment is shown broken away to indicate indeterminate width.

FIG. 2 is a bottom plan view thereof;

FIG. 3 is front elevational view of the garment. The garment is shown broken away to indicate indeterminate length.

FIG. 4 is a left side elevational view thereof;

FIG. 5 is a right side elevational view thereof; and,

FIG. 6 is a front elevational view thereof.

The broken lines depicting the hem detail in FIG. 6 of the drawing views represents environmental structure only and forms no part of the claimed design.
